(57) **CLAIM**

The ornamental design for a toy ball having protruding lobes, as shown and described.

DESCRIPTION

FIG. 1 is a front view of a toy ball having protruding lobes, each elevation view seen at 72° and 144° rotation therefrom being identical to the front view shown;

FIG. 2 is a top view thereof;

FIG. 3 is a bottom view thereof; and,

FIG. 4 is a perspective view thereof.
